UNITED STATES PATENT OFFICE.

JOSEPH H. ROBERTS, OF MANCHESTER, CONNECTICUT.

CLUTCH.

1,360,320.

Specification of Letters Patent. Patented Nov. 30, 1920.

Application filed October 25, 1919. Serial No. 333,223.

To all whom it may concern:

Be it known that I, JOSEPH H. ROBERTS, a citizen of the United States of America, and a resident of Manchester, county of 5 Hartford and State of Connecticut, have invented certain new and useful Improvements in Clutches, of which the following is a full and clear specification.

One object of this invention is to construct 10 both the pulley-receiving friction-cup and the other members of the clutch of separable parts to adapt them for attachment to a shaft at any point along the length thereof without disconnecting the shaft from its 15 hanger, thereby reducing to a minimum the time required to attach a clutch-pulley to a shaft. This invention has other objects in view which will appear in the course 20 of the specification.

In the drawings—

Figure 1 is a longitudinal sectional view;

Fig. 2 is a transverse section on the line 2—2 of Fig. 1;

Fig. 3 is a similar view on the line 3—3 25 of Fig. 1;

Fig. 4 is a side elevation;

Figs. 5 and 6 are detail views of the friction-ring spreader;

Fig. 7 is a sectional view on the line 7—7 30 of Fig. 1; and

Fig. 8 is a perspective view of the upper half of the clutch body as viewed in Fig. 1.

Referring to the drawings by reference-characters, 10 designates the friction-cup 35 which is loosely mounted on the shaft as usual and is provided also as usual at one side with a pulley-receiving hub 11 which is adapted to receive the usual split pulley. This friction-cup and its hub are divided 40 longitudinally into two halves so as to be adapted for ready attachment to the shaft, the securing means consisting of four bolts 12 for the hub and two bolts 13 for the friction-cup, these bolts being passed through 45 radial flanges 14 carried respectively by the cup and the hub, the cup, as well as the hub being recessed so as to position the bolts, together with their nuts and heads, within the peripheral lines of the hub and 50 the cup. By thus setting the bolts 12 within the periphery of the hub, it will be seen that when the pulley is clamped upon the hub, the hub and the pulley will cover the bolts and thus prevent their engaging in the 55 clothing of the attendant engaged in repairing or oiling the clutch. The bolts 13 in the friction-cup will be similarly covered

by an annular dust-guard 15 when the clutch is in operation, as more fully hereinafter set forth.

The friction-cup and the hub are desirably constructed on a wood filling 16 covered and closed in by pressed sheet steel shells 17, the aforesaid flanges 14 being formed by outwardly bending the edges of 60 said shells. In this way, an inexpensive and light structure is provided, and, besides, by oil-treating the wood in a well-known manner, this combined cup and hub will be in a large measure self-lubricating. 65 Any suitable means may be provided for preventing the friction-cup and its hub from sliding on the shaft in a direction away from the clutch mechanism; I have shown in dotted lines in Fig. 4 a split collar 18 for 70 this purpose.

Adjacent the cup side of the friction-cup is affixed to the shaft a clutch-body 19 which is desirably made of pressed sheet steel 75 welded or brazed at the joints and which is constructed in halves so as to be readily clamped on the shaft in abutting relation to the friction-cup, suitable keys 20 or other means being provided for preventing this clutch-body from turning on the shaft. The 80 end of the clutch-body where it enters the friction-cup is reduced in diameter as compared with the main body portion, and upon this reduced tubular part 19' is mounted the split friction-ring 21 which is constructed in any suitable manner, preferably 85 in two sections pivotally connected together by a pivot-pin 22, the open side of this friction-ring being coincident with a flattened shelf 23 formed on the face of the clutch-body, thus forming between the outer face 90 of said shelf and the inner friction-face of the cup and between the ends of the friction-ring a chamber or recess for the reception of the friction-ring-spreading devices 95 hereinafter described. The said flattened member or shelf 23 extends outwardly to near the opposite end of the clutch-body, and at its said outer end is formed a radial shoulder 24 to form an abutment for limiting the outward throw of the shifter-sleeve, as hereinafter set forth. At the outer end of the flattened part 23, adjoining the shoulder 24 is formed a socket 24^a 100 designed to receive a rigid wedge secured 105 to the clutch sleeve, as will be hereinafter described.

The clutch-body is formed of pressed sheet steel and is hollow in order to reduce cost

and decrease the weight to a minimum, said pressed sheet steel sections being welded or brazed together in any suitable manner. The two halves of the clutch-body are 5 adapted to be clamped tightly on the shaft and the keys 20 by means of four bolts 25, two at each side of the shaft, these bolts being arranged in peripheral recesses formed in the exterior of the clutch-body in the 10 same manner as the recesses 14 are formed in the friction-cup and pulley-hub, namely by bending the sheet steel inwardly to form pockets in the periphery of the cylindrical portion of the clutch-body. These bolt-pockets are covered by the shifter-sleeve which is adapted to slide on the clutch-body between the aforesaid shoulder 24 and the adjacent face of the friction-cup.

The shifter-sleeve is desirably formed of 20 pressed sheet steel in two halves, in order that it may be conveniently placed upon the clutch-body after the same and the friction-cup are located on the shaft. This shifter-sleeve is provided with the dust-cap 15, 25 heretofore referred to, which cap extends over upon the periphery of the friction-cup far enough to extend beyond the bolt-recesses 14 therein when the shifter-sleeve is moved into active position. This shifter-sleeve is provided with a metal block 26 riveted or otherwise secured to its inner face and provided with a wedge-shaped nose 27 which is adapted to enter between ring-spreading-levers 28 to thus swing these 30 levers on their pivots and thus spread the friction-ring. The block 26 fits in the socket 24^a to key the sleeve to the clutch body and is adapted to abut against the shoulder 24 to limit the outward movement of the 40 shifter-sleeve on the clutch-body; and, to take the shearing-strain off the rivets, the outer face of this block 26 is provided with an enlargement which fits into an annular depression 29 formed in the inner face of 45 the shifter-sleeve.

The spreading-levers 28 are pivotally mounted on a pin 30 which rises from a disk 31 resting upon the shelf 23 at a point within the friction-cup, said pin 30 being 50 radially arranged and being tapered radially inwardly, so that its outer end is of larger diameter than its inner end. The base-disk 31 of this pin rests loosely on the shelf 23. The spreader-levers are pivotally 55 connected to the pin 30 by being provided with rounded notches in their inner edges, near their inner ends, and they are maintained in pivotal contact with the pin by projections or bosses 32, one being formed 60 on each of the levers, on the outer face near its forward end, in such position as to fit a corresponding notch formed in the adjacent end of the friction-ring, and to impinge against the wall thereof, the contacting faces of the friction-ring and the

boss 32 being inclined oppositely to the angle of the face of the pin 30, so that each lever is virtually dove-tailed between the pin 30 and the adjacent end of the friction-ring. Each lever rests, through the medium 70 of a screw 33, upon the disk-base 31, so that by turning this screw the lever may be moved nearer to or farther from the center of rotation and thus vary the pressure upon the friction-ring with a given thrust by 75 means of the wedge 27. It will be observed that when the wedge 27 is thrust between the levers 28, they will be rocked on the pivot-pin 30 and their bosses 32 will be swung slightly outwardly and forwardly, so impinging against the adjacent inclined faces of the ends of the friction-ring and the pin and its base will be moved slightly toward the wedge. In addition to being inclined in a direction opposite to the face 85 of the pivot-pin 30, each end of the friction-ring is inclined toward the inner wall of the friction-cup, so that movement of the bosses 32 toward said inner wall will spread the friction-ring and bring its frictional faces into contact with the frictional faces of the friction-cup. I have shown the projections 32 as being bosses cast or formed on the levers 28, but it will be understood that I may mount friction-rollers in the 90 levers in such manner that these rollers shall impinge against the inclined faces of the friction-ring sections and thus eliminate a part of the friction engendered in spreading the friction-ring.

It will be observed also that the dovetailing of the spreading-levers between the friction-pin and the adjacent faces of the friction-ring ends serves to hold the levers in place and thus avoids the use of extraneous fastening devices.

The double-walled sheet steel shifter sleeve is divided longitudinally into two halves or sections semicircular in transverse section, and the outer wall of each 110 section is pressed inwardly to form two semicircular chambers 35 in each half of the sleeve at opposite sides of a semicircular channel 34. The channels 34 of the two half sections form an annular groove or channel 115 for the usual shifter fork. The shifter-sleeve is, as stated, made in halves, and these two halves are clamped loosely upon the clutch-body by means of four bolts 36, these bolts being set back in recesses formed in the annular chambers 35 so as to avoid forming obstructions on the periphery of the shifter-sleeve. The clamping faces for the bolts are formed by cutting U-shaped slots 44 in the sheet metal outer wall of 120 each chamber 35 to form tongues 37, the tongues being then bent inwardly and welded or brazed to the inner wall of the shifter-sleeve, as shown in Fig. 3. The openings in the shifter-sleeve, thus formed 125

are closed by means of sliding closure-plates 38 made desirably of spring steel and adapted to slide in the annular chamber 35, the inner end of each plate 38 being folded upon itself to form a loop 39 adapted to slide within the channel 35. These closure-plates 38 are curved to conform to the curvature of the outer face of the shifter-sleeve, and the free end of each plate is adapted to engage under the adjacent nut (or head) of one of the bolts 36. By thus providing for closing the bolt-recesses formed in the exterior of the shifter-sleeve and by also providing closure means for the recesses for bolts 12 and 13, it will be observed that when the clutch is in action there will be no projecting faces on the periphery of any of its parts to catch in the clothing of operatives who may be inspecting or repairing or oiling the clutch.

To form more substantial clamping faces for the shifter-sleeve sections than would be afforded by the bent-in parts 37 alone, I weld or braze in each end of the chambers 35 an additional member 40 consisting of a piece of sheet steel bent to conform to the curvature of the walls of the channel 35 and the inwardly-bent tongue 37. These sheet steel members 40 serve to close the ends of the channels 35 and afford substantial abutment faces for the shifter-sleeve sections when they are clamped together by the bolts 36, said bolts 36 passing entirely through the sheet steel members 40 and also the inwardly-turned tongues 37.

It will be understood that instead of the two-part pivoted friction-ring shown, I may employ the well-known one-piece elastic friction-ring, and also that many other minor changes in construction may be resorted to without departing from the spirit of the invention as defined in the claims appended.

For convenience in adjusting the screws 32, I provide the friction-cup with a radial passage 41 in alignment with the screws 33, so that by rotating the friction-cup its passage 41 may be brought into radial alignment with either one of the screws 33, thereby permitting a screw-driver to be inserted through passage 41. This manner of adjusting the spreader-levers bodily radially for the purpose of increasing or decreasing the pressure of the friction-ring on the cup, it will be obvious, not only provides a simple manner of adjustment but also provides a wide range of adjustments. It will be observed that the inner face of the cup is provided with two annular friction-faces, one 42 facing inwardly toward the shaft and the other 43 being arranged substantially at right angles to said face 42, so as to face toward the end of the shaft, the face 42 being at a very obtuse angle to the axis 45 of the shaft, while the face 43 stands at a

very acute angle with reference thereto. In operation, the friction-ring will first engage the inwardly-facing face 42, and then the ring will slide inwardly until it jams against the endwisely-facing face 43, the inclination of the face 42 serving virtually to wedge the friction-ring against the end-face 43, thereby greatly promoting the friction between the ring and the cup. This arrangement of a double friction face is particularly advantageous in that it insures a quick smooth picking-up action when the clutch is thrown in, as is obvious.

The nature and scope of the invention having been thus indicated and its preferred embodiment having been specifically described, what is claimed as new is:

1. A clutch member for friction clutches comprising a pressed steel cylinder having a reduced portion forming a pulley-receiving hub, and a filling of rigid material extending from end to end of the cylinder and provided with an axial shaft-receiving bore, said bore being enlarged at one end to form a recess in the outer face of the larger end of the clutch member the walls of which form a friction surface, and the ends of said cylinder being turned inwardly to form annular flanges engaging the ends of said filling.

2. A clutch member for friction clutches comprising a pressed steel cylinder having a reduced portion forming a pulley-receiving hub, a filling of rigid material extending from end to end of the cylinder and provided with an axial shaft-receiving bore, said bore being enlarged at one end to form a recess in the outer face of the larger end of the clutch member the walls of which form a friction surface, and the ends of said cylinder being turned inwardly to form annular flanges engaging the ends of said filling, said member being divided longitudinally into two half sections having recesses in their outer surfaces, and fastening devices detachably connecting said half sections together and having their outer ends housed in said recesses.

3. In a clutch, a friction-cup made in halves, bolts for clamping these halves upon a shaft, the heads and nuts of these bolts being located in recesses formed in the periphery of the friction-cup, and a shifter-sleeve provided with a dust-cap spanning the space between the shifter-sleeve and the friction-cup and extending over upon the outer face of the friction-cup so as to thereby cover the aforesaid recesses when the shifter-sleeve is in active position.

4. A clutch comprising two members of general cylindrical form and provided with axial shaft-receiving passages, one of said members having an internal gripping surface extending around its shaft passage and the other member being formed of pressed steel and having inner and outer walls

- spaced apart, both of said members being divided longitudinally into half sections, means for detachably connecting the half sections of the members together, a double-walled pressed steel shifter sleeve slidable on said pressed steel clutch member divided longitudinally into half sections and having an annular fork channel, means for detachably connecting the sections of said sleeve together, and means rotatable with the pressed steel member operable by the shifter sleeve for gripping and releasing the internal gripping surface of the other clutch member.
15. A clutch comprising two members of general cylindrical form and provided with axial shaft-receiving passages, one of said members having an internal gripping surface extending around its shaft passage and the other member being formed of pressed steel and having inner and outer walls spaced apart, both of said members being divided longitudinally into half sections, means for detachably connecting the half sections of the members together, a double-walled pressed steel shifter sleeve slidable on said pressed steel clutch member divided longitudinally into half sections and having an annular fork channel, means for detachably connecting the sections of said sleeve together, said pressed steel member having a reduced portion at one end extending within the other member and having a part of the outer wall of one section thereof flattened, a divided friction ring surrounding the reduced end portion of the pressed steel member, and ring-expanding means mounted on the flat surface of said pressed steel member and operatively connected with the shifter sleeve.
6. A clutch comprising two members of general cylindrical form and provided with axial shaft-receiving passages, one of said members having an internal gripping surface extending around its shaft passage and the other member being formed of pressed steel and having inner and outer walls spaced apart, both of said members being divided longitudinally into half sections, means for detachably connecting the half sections of the members together, a double-walled pressed steel shifter sleeve slidable on said pressed steel clutch member divided longitudinally into half sections and having an annular fork channel, means for detachably connecting the sections of said sleeve together, said pressed steel member having a reduced portion at one end extending within the other member and having a part of the outer wall of one section thereof flattened, a divided friction ring surrounding the reduced end portion of the pressed steel member, a pair of ring-expanding levers pivotally mounted on the flat surface of the pressed steel member, and a lever-spreading wedge held to one section of the shifter sleeve and slidable over the flattened surface of the steel member, said member being formed with a longitudinal channel closed at its outer end in which the wedge is slidably held.
7. In a clutch, a sheet steel body for receiving the shifter-sleeve, said body being made in sections and each section being hollow and being formed of sheet steel.
8. In a clutch, a sheet steel shifter sleeve having inner and outer walls and end walls, the outer wall being pressed inwardly intermediate the ends of the sleeve to form a shifter-fork channel extending circumferentially of the sleeve.
9. In a clutch, a clutch-body, a friction-cup, and a shifter-sleeve arranged on said body and consisting of sheet steel sections clamped over said body, said body being provided with a radial shoulder adapted to limit the outward movement of the sleeve in a direction away from the cup.
10. In a clutch, a sheet steel shifter sleeve having inner and outer walls and end walls, the outer wall being pressed inwardly intermediate the ends of the sleeve to form a shifter-fork channel extending circumferentially of the sleeve, said sleeve being divided longitudinally into two half sections, and fastening devices for detachably connecting the sections of the sleeve with each other.
11. In a clutch, a friction-cup, a clutch-body, a shifter-sleeve mounted on the body, spreader-levers adapted to be actuated by the shifter-sleeve, a friction-ring adapted to be spread by said levers, and a pivotal support for the inner ends of said spreader-levers consisting of a radial pin tapered inwardly, the adjacent end of the friction-ring being inclined in a direction opposite to the taper of the pin, a screw being provided for each spreader-lever for bodily adjusting it radially inwardly and outwardly between said pin and the coöperating face of the friction-ring, for the purpose set forth.
12. In a clutch, a pair of clutch members divided longitudinally into sections having recesses in the periphery thereof adjacent their meeting edges, fastening devices detachably connecting said sections of the clutch members having their outer ends housed in said recesses, and a shifter sleeve slidable on one of said members and formed with an annular hood at one end adapted to embrace the other member, said sleeve and hood being adapted to cover the recesses in said clutch members.
13. In a clutch, a shifter-sleeve made in halves to adapt it to be clamped over the body of the clutch, said shifter-sleeve being hollow and provided with openings in its outer wall, bolts for fastening the halves upon the clutch-body, these bolts and their nuts and heads being located in the

hollow portions of the shifter-sleeve, and closure devices mounted in the shifter-sleeve adapted to close said openings in the outer wall of the shifter-sleeve to make the outer 5 peripheral surface of the shifter-sleeve substantially continuous and free of obstructions.

14. In a clutch, a shifter-sleeve made in halves adapted to be clamped over the body 10 of the clutch, clamping bolts whose heads and nuts are located in recesses formed in the shifter-sleeve, and closure devices for these recesses to render the outer surface of the shifter-sleeve substantially continuous 15 and free of obstructions.

15. In a clutch, a clutch member having an internal friction surface and a reduced pulley-receiving hub, a second clutch member having one end housed within the other 20 clutch member, said members being divided

longitudinally into sections having recesses in the periphery thereof adjacent their meeting edges, fastening devices connecting said sections having their ends housed in said recesses, an expansible friction ring rotatable with the second clutch member and located between the periphery of said member and the friction surface of the other member, a shifter sleeve slidable on the second clutch member, ring-expanding means 30 operable by said sleeve, and an annular hood carried by the sleeve, said sleeve and hood being adapted to cover the ends of the fastening devices in the second clutch member and in the larger portion of the other clutch 35 member and also the ring-expanding means.

In testimony whereof I hereunto affix my signature.

JOSEPH H. ROBERTS.
